(57) **CLAIM**

I claim the ornamental design for a bracket, as shown and described.

DESCRIPTION

FIG. 1 is a perspective view of a bracket showing my new design;

FIG. 2 is a front elevation view thereof;

FIG. 3 is a back elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a view showing the bracket, hung on a vehicle while holding a hole cutter.

The broken lines in FIG. 8 depicting a vehicle and hole cutter are included for the purpose of illustrating the environmental structure and form no part of the claimed design.
